UNITED STATES PATENT OFFICE.

WALTER H. BAILEY, OF NORTH ANDOVER, MASSACHUSETTS, AND ISAAC SNOW, OF PHILADELPHIA, PENNSYLVANIA, ASSIGNORS TO DRAPER COMPANY, OF HOPEDALE, MASSACHUSETTS, A CORPORATION OF MAINE.

SHUTTLE-CHECK.

SPECIFICATION forming part of Letters Patent No. 716,514, dated December 23, 1902.

Application filed December 28, 1901. Serial No. 87,528. (No model.)

To all whom it may concern:

Be it known that we, WALTER H. BAILEY, residing at North Andover, in the county of Essex and State of Massachusetts, and ISAAC SNOW, residing at Philadelphia, in the county of Philadelphia and State of Pennsylvania, citizens of the United States, have invented an Improvement in Shuttle-Checks, of which the following description, in connection with the accompanying drawings, is a specification, like characters on the drawings representing like parts.

This invention has for its object the production of novel means for checking the movement of a shuttle as it enters the shuttle-box of the loom and for preventing the rebound of said shuttle, the devices of the invention operating to bring the shuttle to rest at a substantially predetermined point.

The various features of the invention will be more fully hereinafter described, and pointed out in the claims.

Figure 1 is a top or plan view, partly broken out, of the left-hand end of the lay of a loom with one embodiment of our invention applied thereto. Fig. 2 is a rear elevation of the parts shown in Fig. 1. Fig. 3 is a right-hand end elevation of the lay and adjacent parts shown in Fig. 2; and Fig. 4 is a section 30 on the line $x-x$, Fig. 2.

We have herein shown the lay A^3 as having a shuttle-box thereon comprising a front plate or wall B , the back wall B' , an overhanging shuttle-guard B^3 , and a binder B^x , pivotally mounted near the outer end of the lay at b^x , and these parts are or may be of any usual or well-known construction. The lay is longitudinally slotted at A^x for the staff of the usual picker P . The usual protector rock-shaft p is shown as mounted in bearings p^x beneath the lay and has mounted thereon the dagger p' and the rocker-arm p^2 , having the upturned finger p^3 to bear against the free end of the binder, the action of said rock-shaft being controlled by a spring S^x , which surrounds the shaft and acts to hold the finger p^3 against the binder, as usual in this class of devices.

In our present invention we have provided 50 in addition to the spring-controlled rock-

shaft p , which serves to exert a certain force upon the binder B^x as it is thrown outward by the impact of the entering shuttle, a spring-controller for the binder, which is in the nature of a binder-spring, and means 55 which are rendered operative by the momentum of the shuttle after the shuttle has come in contact with the binder to increase the tension of the binder-spring. Normally the binder-spring is out of contact with the 60 binder, so that the only force to which the binder is subjected is the spring-controlled rock-shaft 9 . When, therefore, a shuttle enters the shuttle-box and contacts with the binder, the said binder is subjected to the pressure 65 exerted by the spring-controlled rock-shaft, and as the shuttle continues its movement the binder is thrown into engagement with the binder-spring and is subjected to the pressure of the binder-spring in addition to that of 70 the rock-shaft. When the shuttle nears the end of its flight, means are brought into operation to increase the tension of the binder-spring sufficiently to bring the shuttle to rest and prevent its rebound.

Secured upon the back of the lay is a suitable bracket 3 , to which is pivoted in any suitable way a spring-supporting member 4 , this member being conveniently shown as pivoted between lugs or ears 5 upon the 80 bracket 3 . Secured to the spring-supporting member 4 is a spring S , which is adapted to engage the binder and which operates as a binder-spring. An actuating-lever 6 is also pivoted to the bracket 3 and has a tail or 85 cam extension 7 , which engages the spring-supporting member 4 , an arm 8 of the lever 6 extending across the path of the picker P , as illustrated in the drawings. The tail or cam portion 7 of the lever 6 is confined between 90 ears or flanges 9 upon the end of the spring-supporting member 4 , said ears or flanges operating to hold the lever 6 and member 4 in operative position. The lever 6 has the flat face 10 , which normally engages a flat 95 face on the spring-supporting member 4 , and when the parts are in this position the arm 8 of the lever stands across the path of the picker-staff, while the end of the spring S is slightly separated from the binder, as seen in 100

Fig. 1. The spring in its normal position therefore exerts no pressure upon the binder.

When the shuttle enters the shuttle-box, as shown in dotted lines, Fig. 1, it strikes the 5 swell of the binder B^x and throws the latter outward with great violence, such outward movement of the binder being opposed by the action of the spring S^x on the rock-shaft p . As soon as the binder is thrown outward 10 slightly it comes into contact with the spring S and the tension of said spring is added to that of the spring S^x , so that at this point the pressure against the binder is that resulting from the two springs $S S^x$. As the 15 shuttle continues its movement it strikes the picker and the latter is moved with the shuttle. Such impact of the shuttle upon the picker drives the picker-staff backward and forces the same against the arm 8 of the lever 20 6, thereby swinging said lever into the dotted-line position, Fig. 4. This action of the lever 6 operates, through the cam or tail portion thereof, 7, to swing the spring-supporting member 4 into the dotted-line position, there- 25 by forcing the spring S against the binder with a greater degree of tension. It will thus be seen that as the binder is thrown outward by the impact of the shuttle it is subjected to three distinct degrees of pressure—first, the 30 pressure generated by the action of the spring S^x ; second, the pressure generated by the continued action of the spring S^x and the added action of the spring S , and third, by the continued action of the springs S^x and S and the 35 further or increased action of the spring S occasioned by the shuttle-induced movement of the picker. The force with which the entering shuttle strikes the binder is sometimes sufficient to throw the said binder outwardly 40 far enough to cause it to lose contact with the shuttle for an instant, and while the action of the springs $S S^x$ would bring the binder back against the shuttle almost instantly, yet this action is accelerated by the shuttle-induced 45 movement of the picker against the lever 6, the said cam-lever 6 operating to increase the tension upon the binder-spring sufficiently to bring the binder hard enough against the shuttle before the shuttle has had time to re- 50 bound to bring the shuttle to rest and prevent any rebound.

By the expression "tension of the binder-spring" as used in the specification and claims we mean the pressure of the spring 55 due solely to the internal strains to which the spring is subjected, or, in other words, pressure which is applied to the binder solely by the binder-spring. Any change of the tension of the binder-spring, however, will 60 result in a change of the flexure of the spring. When the tension of the binder-spring is increased, the flexure of the spring will also be increased, and vice versa. Our invention therefore comprises means for increasing the 65 tension of the binder-spring after the shuttle has come in contact with the binder, such

means being rendered operative by the impact of the shuttle.

While we have herein illustrated one simple mechanism in which our invention may 70 be embodied, yet we do not wish to be limited to the exact construction shown, as the details thereof may be varied in various ways without departing from the spirit of the invention as expressed in the appended claims. 75

Having fully described our invention, what we claim as new, and desire to secure by Letters Patent, is—

1. In a loom, a shuttle-box, a binder, a binder-spring, and means actuated by the 80 impact of the entering shuttle subsequent to its contact with the binder, to adjust the tension of the binder-spring in proportion to the momentum of the shuttle.

2. In a loom, a shuttle-box, a binder, a binder-spring, and means governed by or 85 through the entering shuttle to increase the tension of the binder-spring throughout its entire extent, whereby the pressure of the spring upon the binder is increased. 90

3. In a loom, a shuttle-box, a binder, a binder-spring, and means actuated by the impact of the entering shuttle subsequent to its contact with the binder to increase the flexure of the spring, whereby the pressure 95 of said spring upon the binder is increased.

4. In a loom, a shuttle-box, a binder, a binder-spring, and means rendered operative after the shuttle has contacted with the binder to increase the flexure of the spring in proportion to the momentum of the entering shuttle, whereby the pressure of the spring upon the binder is increased. 100

5. In a loom, a shuttle-box, a binder, a binder-spring, a movable support therefor, 105 and means rendered operative by the entering shuttle to shift the support and thereby increase the tension of the binder-spring.

6. In a loom, the lay, a shuttle-box thereon, a binder, a pivotally-mounted binder-spring, 110 and means operated by or through the impact of the entering shuttle upon the picker to increase the tension of said spring.

7. In a loom, the lay, a shuttle-box thereon, a binder, a binder-spring, and a cam-lever 115 coöperating with the spring, said cam-lever being constructed to be actuated by the shuttle-induced movement of the picker and operating to increase the pressure of the spring upon the binder. 120

8. In a loom, the lay, a shuttle-box thereon, the binder, a spring-supporting member pivoted to the lay, a binder-spring connected therewith, a cam-lever mounted on the lay and coöperating with said spring-supporting 125 member, said cam-lever being normally in the path of the picker, whereby as the picker is thrown backward by the impact of the incoming shuttle, the cam-lever is operated to thereby bring the spring-supporting member in 130 such a position as to increase the action of the spring upon the binder.

9. In a loom, the lay, a shuttle-box thereon, a binder, a spring-controlled rock-shaft mounted on the lay, and having a finger in engagement with the binder to resist outward movement of said binder, a binder-spring normally exerting no appreciable pressure on the binder, and means to positively increase the action of the binder-spring as the shuttle ends its flight, the construction being such
- 5 that the initial outward movement of the binder is resisted by the spring-controlled rock-shaft alone, and thereafter the continued outward movement is resisted by both the spring-controlled rock-shaft and the binder-spring, and the action of said binder-spring is increased as the shuttle ends its flight.
10. In a loom, a binder, a binder-spring, and means governed by or through the shut-

tle on each incoming pick thereof and rendered operative subsequent to the contact of 20 the shuttle with the binder to automatically adjust the tension of the spring in proportion to the shuttle speed prior to engagement of the shuttle and binder.

In testimony whereof we have signed our 25 names to this specification in the presence of two subscribing witnesses.
